Atty.

UNITED STATES PATENT OFFICE.

GLENN A. BREWER, OF KANSAS CITY, MISSOURI.

AEROPLANE.

1,307,806.

Specification of Letters Patent. Patented June 24, 1919.

Application filed January 16, 1919. Serial No. 271,378.

To all whom it may concern:

Be it known that I, GLENN A. BREWER, a citizen of the United States, residing at Kansas City, in the county of Jackson and State of Missouri, have invented certain new and useful Improvements in Aeroplanes, of which the following is a specification.

This invention relates to aeroplanes and has for its object to produce a machine of this character having a motor adapted for exerting lifting force to coöperate with the usual elevating and sustaining equipment in effecting upward travel and to retard vol-
10 plane travel to permit a landing to be safely accomplished at less travel speed than is usually required. A further object is to pro-
15 vide an aeroplane equipped with rotating means susceptible of being pitched laterally to a slight angle for the purpose of offering
20 resistance to lateral drift in traveling trans-
versely of air currents, and thus permit a machine to be driven in an undeviating course without pointing and driving it at an
25 angle oblique to the actual course of travel as is now necessary with the conventional aeroplane or other aerial vessel.

With these general objects in view the invention consists in certain novel and useful features of construction and combinations of
30 parts as hereinafter described and claimed; and in order that it may be fully understood reference is to be had to the accompanying drawing, in which:

Figure 1, is a fragmentary side elevation of an aeroplane embodying my invention, part of the covering of the fuselage being broken away and certain of the other parts being shown in section to more clearly disclose the novel features of the invention.

40 Fig. 2, is a top plan view of the construction as illustrated in Fig. 1.

Fig. 3, is a cross-section on the line III—III of Fig. 2.

Fig. 4, is an enlarged section taken on the
45 line IV—IV of Fig. 5.

Fig. 5, is a section on the same scale as Fig. 4, and taken substantially on the line V—V of Fig. 4.

Referring to the drawing in detail 1 indi-
50 cates the body or covered fuselage of an aeroplane of any suitable type, that shown being of the bi-plane type but disclosing only the lower plane 2. The drawing also shows the machine as of the tractor type, 55 that is with the propeller 3, in front, but it is to be understood that the location of the propeller is immaterial.

The body is formed at a suitable point, preferably about centrally between the planes of the front and rear edges of plane 2 with a vertical opening 4, and rigidly secured in said opening is a skeleton frame, the same being preferably constructed as follows: 5 is a ring of single or double type as preferred, arranged vertically in the plane 60 of the longitudinal axis of the body, and provided with lugs 6 bolted or otherwise secured to the body. Said ring may be fixed in position by other means if desired. 7 is a ring fitting snugly within and transversely 65 of ring 5, and rigidly secured to the same and to the fuselage as shown or in any other suitable manner, the ring 7 being shown as provided with angle brackets 8 bolted to the fuselage at opposite sides of opening 4. 70 The fixed ring 7 of the frame is preferably 75 of channel form, and fitting rotatably in the channel of said ring 9.

A rotating motor 10 of the Gnome or any equivalent type is arranged with said skeleton frame, and the pistons of the cylinders of the motor are connected as customary in the type of engines mentioned to the crank of the vertical shaft 11, which shaft is rigidly secured at its ends to the inner or rotatable ring 9 and hence is capable through turning adjustment of said ring, of being tilted to the right or the left at the will of the operator, for a purpose hereinafter set forth. The detail construction of the engine, 80 such as pistons, the crank of said shaft, the connections between the pistons and crank, and the other conventional features of the engine are omitted as of common and well-known construction, the motor differing 85 however in one particular, namely in having the lower faces of its cylinders inclined transversely with respect to the length of said cylinders, as at 12, it being noted that the inclined planes 12 are similar so that 90 when the engine is turned in the direction indicated by the arrow, Fig. 2, all of said planes will coöperate in exerting force tending to lift the machine. 100

The crank case or central portion of the engine or motor is provided at its upper side with a bevel gear 13, meshing with a smaller bevel gear 14 secured on one end of the shaft 15 for the propeller 3; said shaft being journaled in any suitable manner and ex- 110 tending radially with respect to the axes of the circular frame, so that when the motor is tilted toward one side or the other through the rotative adjustment of the ring 9, the

bevel gear 13 will turn concentrically with respect to the axes of the propeller shaft, so that the tilting of the motor in nowise affects the position or operation of the gear 14, shaft 15 and propeller 3.

To effect the tilting of the motor either to the right or the left any suitable mechanism may be employed, that illustrated being constructed as follows: 16 is a worm 10 rack secured within the adjustable ring 9, and engaged by a worm wheel 17 rigidly secured to a bevel gear 18 journaled on the stub shaft 19 carried by and forming a part of a bar 20 secured to a pair of angle 15 brackets 21 fastened rigidly to the ring 5, one of said brackets also forming a journal bearing for a longitudinal shaft 22 equipped at its front end with a bevel gear 23 meshing with bevel gear 18. The rear end of the 20 shaft 22 is equipped with a hand wheel 24 or the like so that the person in control of the machine may readily turn shaft 22 and thus through the intermeshing gears 23 and 18 and the worm wheel 17 and worm 16, 25 turn ring 9 toward one side or the other for the purpose of tilting the shaft 11 in the proper direction and the motor in the desired direction.

In operation the motor will normally operate in a horizontal plane and through the beveled or inclined lower faces of the cylinders, will exert a lifting force which assists in sustaining the plane, this being particularly desirable when landings are being 30 made, as it will enable a landing to be made at less travel speed than would otherwise be required. It is also obvious that when rotating the cylinders will have a gyroscopic effect, and tend to maintain the machine in an upright position. When traveling across air currents, the motor can be tilted in the proper direction to exert force tending to resist drifting, and thus permit the machine to be started in a direct line 35 instead of an angle to the course of travel desired, as is now necessary with all aerial vessels.

It will be apparent of course that the motor will not necessarily have to be located centrally of the machine, and it is clearly obvious that there may be two or more of such motors. It will also be understood that instead of providing the cylinders of the motor with inclined lower faces, 50 a horizontal propeller may be secured to the motor shaft, which in principle of course is identical with the construction and mode of operation of the motor described.

From the above description it will be apparent that I have produced an aeroplane embodying the features of advantage set forth as desirable, and it is obviously sus-

ceptible of modification without departing from the principle of invention involved or from the spirit and scope of the appended 65 claims.

I claim:

1. An aeroplane comprising crossed rings, one of which is disposed transversely of the machine, a ring arranged for rotation with- 70 in the transversely disposed ring, a vertical shaft secured at its upper and lower ends in said rotatable ring, a series of cylinders arranged and adapted to rotate around said shaft in a plane at right angles to the axis 75 of said shaft, the bottoms of said cylinders being similarly inclined transversely of their axes, a propeller geared to and adapted to be driven by the cylinders when the same are rotated, and means for imparting turning movement in one direction or the other to said rotatable ring to effect tilting of the motor and the shaft toward one side or the other.

2. An aeroplane provided with a vertical 85 opening, a skeleton frame secured in said opening, a circular ring arranged transversely of the aeroplane and adapted to be turned within said skeleton frame, a vertical shaft secured at its upper and lower 90 ends in said adjustable ring, a series of cylinders arranged and adapted to rotate around said shaft in a plane at right angles to the axis of said shaft, the bottoms of said cylinders being similarly inclined 95 transversely of their axes, a propeller geared to and adapted to be driven by the cylinders when the same are rotated, and means for imparting turning movement in one direction or the other to said adjustable ring 100 to effect tilting of the motor and the shaft toward one side or the other.

3. An aeroplane provided with a vertical 105 opening, a skeleton frame secured in said opening, a circular ring arranged transversely of the aeroplane and adapted to be turned within said skeleton frame, a vertical shaft secured at its upper and lower ends in said adjustable ring, a series of cylinders arranged and adapted to rotate around said shaft in a plane at right angles 110 to the axis of said shaft, the bottoms of said cylinders being similarly inclined transversely of their axes, a propeller geared to and adapted to be driven by the cylinders 115 when the same are rotated, a rack formed on the adjustable ring, and a hand operated shaft suitably journaled and geared to said rack for effecting turning adjustment toward one side or the other of said ring to 120 effect the tilting of said motor.

In testimony whereof I affix my signature.

GLENN A. BREWER.
